UNITED STATES PATENT OFFICE.

JOHN FRANCIS CLARK, OF NEW ORLEANS, LOUISIANA.

DESIGN FOR A COTTON-TIE BUCKLE.

SPECIFICATION forming part of Design No. 24,754, dated October 15, 1895.

Application filed September 10, 1895. Serial No. 562,112. Term of patent 14 years.

To all whom it may concern:

Be it known that I, JOHN FRANCIS CLARK, a citizen of the United States, residing at New Orleans, in the parish of Orleans and State of Louisiana, have invented a new and original Design for Cotton-Tie Buckles, of which the following is a specification.

- This invention relates to a new and original design for cotton-tie buckles; and it has for its object to provide a design of this character that shall be both useful and ornamental.

The leading feature of the design resides in a flat body provided at its longitudinal side edges and on one of its flat faces with continuous longitudinal superficial rounded ribs, a series of parallel transversely-disposed oblong figures arranged between the superficial ribs, one of said figures being provided at one end with an acute angle or V-shaped portion, and an obliquely-disposed open space leading from one of the oblong figures to one end of the flat body and bounded between parallel oblique lines.

In the drawings, Figure 1 is a plan view of a buckle embodying the herein-described de-

sign. Fig. 2 is a transverse sectional view thereof.

In the accompanying drawings the numeral 1 designates the flat buckle-body provided at its longitudinal side edges and on one of its flat faces with continuous longitudinal superficial rounded ribs 2. Between the ribs 2 are arranged a series of parallel transversely-disposed oblong figures 3, provided with rounded ends 4, and one of which oblong figures is provided at one of its ends with an acute-angle or V-shaped portion 5. An obliquely-disposed open space 6 leads from one side of one of the figures 3 out to one end of the body 1, and is bounded between the parallel oblique lines 7. 40

What I claim is—

The design for a cotton-tie buckle herein shown and described.

In testimony that I claim the foregoing as my own I have hereto affixed my signature in 45 the presence of two witnesses.

JOHN FRANCIS CLARK.
